CLAIM

The ornamental design for a decanter set, as shown and described.

DESCRIPTION

FIG. 1 is a top, front, right side perspective view of a decanter set showing our new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of the portion labeled "9" in FIG. 1.

The dash-dash broken lines in the drawings depict portions of the decanter set that form no part of the claimed design. The dot-dot broken lines shown in FIGS. 1 and 9 designating the boundary of the enlarged view form no part of the claimed design. The dot-long dash-dot broken lines in FIG. 7 depict portions of the decanter set that form no part of the claimed design.
